(57) **CLAIM**

I claim the ornamental design for a mounting system for use with audio/visual devices or the like, as shown and described.

DESCRIPTION

FIG. 1 is a perspective view of a mounting system for use with audio/visual devices or the like showing my new design, wherein the break lines indicate that no specific length is being claimed;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The ornamental design which is claimed is shown in solid lines in the drawings. The broken lines in the drawings are for illustrative purposes only and form no part of the claimed design.
